PARK E. WELTON, OF CUYAHOGA FALLS, OHIO, ASSIGNOR TO KATHARINE B. WELTON,
OF CUYAHOGA FALLS, OHIO.

FEED MECHANISM FOR MIXING-MILLS.

1,173,626.

Specification of Letters Patent. Patented Feb. 29, 1916.

Application filed March 8, 1915. Serial No. 12,794.

To all whom it may concern:

Be it known that I, PARK E. WELTON, a citizen of the United States, residing at Cuyahoga Falls, in the county of Summit 5 and State of Ohio, have invented a certain new and useful Improvement in Feed Mechanism for Mixing-Mills, of which the following is a full, clear, and exact description.

When an endless feed apron is applied to 10 a rubber mixing mill for the purpose of catching the plastic rubber compound which drops after passing between the mixing rolls and returning said compound to said mixing rolls, one great obstacle to the practical success of said feed apron and its associated mechanism is the disposition of said apron to travel faster at one edge than at the other, and, consequently, to acquire a sidewise movement which, if not controlled, will soon render the feed mechanism inoperative. This is due to the fact that the plastic rubber compound, when it drops onto the feed apron, does not spread itself evenly upon the same from side to 20 side, but, on the contrary, is in the form of lumps which fall haphazard on the apron at various places between its sides. If, for example, a thick lump of the rubber compound falls into the apron near its front 25 side, this lump will be carried between the apron and the surface of that mixing roll which drives it. This lump in effect increases the diameter of said driving roll at this point, and therefore imparts to the 30 front edge of the apron a rate of travel which exceeds that of the rear edge of the apron. In other words, the effect upon the apron is substantially as if the apron driving mixing roll, instead of being a true 35 cylinder, were shaped irregularly with its greatest diameter sometimes near one end and sometimes near the other, and sometimes at all sorts of unexpected points between said ends.

The primary object of this invention is 40 to provide mechanism which will permit the two edges of the mixing apron to travel at any required relative rates while in contact with said mixing roll, but which will 45 prevent such inequalities of movement from extending throughout the length of the apron, or, in other words, to compel the apron to move at equal rates from side to side at all points in its length except the 50 parts which are in contact with or immedi-

ately adjacent to the apron driving mixing roll, and yet to permit such inequalities of movement of that part of the apron which is in contact with the mixing roll as is necessary under the stated circumstances. 60

The invention consists in the construction and combination of parts shown in the drawings, and hereinafter described and pointed out in the appended claims.

In the drawings, Figure 1 is a sectional 65 side elevation of the invention; Fig. 2 is a sectional end view in the plane indicated by line 2-2 of Fig. 1; Fig. 3 is a view, from the left end of Fig. 1, of one of the standards 45 and the parts associated therewith and the adjacent rod 15; Fig. 4 is a plan view of the apron feeding mechanism 70 disassociated from the mixing mill and sectioned in plane of line 4-4 of Fig. 1.

Referring to the parts by reference characters, 1 and 2 represent the mixing rolls of an ordinary rubber mixing mill. No attempt has been made to show the mechanism by which these rolls are turned because that is no part of the present invention. It 75 must be assumed, however, that suitable mechanism is associated with these rolls to cause them to turn at the proper rate in the directions indicated by the arrows placed on said rolls in Fig. 1.

In order that any rubber mixing mill 80 may be quickly equipped with this invention, the feed apron 3 and the mechanism associated therewith are, with the exception of certain standards, 45, all mounted and 85 supported on a pan 10, which may be placed and secured in proper position beneath the mixing rolls.

The endless feed apron 3 runs over three 90 apron rolls 4, 5, 6, whose axes are parallel 95 with the axes of the mixing rolls; and said apron rolls are so mounted that they may assume the operating position relative to the mixing rolls which is shown in Fig. 1, whereby the apron will pass beneath the 100 two mixing rolls, and then be held against a part of the surface of the mixing roll 1, which therefore serves as the apron driving roll and causes the contacting feed apron to travel at the same surface speed. 105

The roll 4 is mounted in bearing brackets 7 which are fixed respectively to two parallel bars 8 located adjacent to opposite sides of the pan. These bars are 110 slidable endwise in brackets 12 and 13 fixed to the

sides of the pan near the ends of the latter. The roll 5 is rotatably mounted in bearings carried by the brackets 13.

Two arms 14 are pivoted respectively to these same brackets 13 on axes which are substantially coincident with the axis of the feed roll 5. Rods 15 secured to these arms 14 extend upward at an inclination toward the mixing roll 1, and at their upper ends 10 they overhang said mixing roll. The roll 6 is rotatably mounted at its ends in bearings carried by two sleeves 16 which are respectively slidable upon the two rods 15.

At the upper end of each of the rods 15 is a sheave 17. A cable 18 is fixed to each of the sleeves 16, and passes upward over the associated sheave 17, thence down to a sheave 19 mounted in brackets on the under side of the pan, and thence to a winding 20 drum 20. The two winding drums are fixed to a horizontal shaft mounted in suitable bearings 21 which are secured and project downward from the bottom of the pan. The two drums 20 are fixed to a shaft 22 which carries near its middle a pinion 23, and this is engaged by a rack bar 24 fixed to the piston rod 25 of a pneumatic cylinder 26, which is preferably supported from the under side of the pan. When air is admitted to this cylinder through the air inlet 27, the piston which is shown by dotted lines in Fig. 1 will be yieldingly pushed toward the opposite ends of the cylinder, and thereby the shaft 22 and the winding drums thereon 30 will be turned in the direction to wind up the cable 18 and thereby apply an elastic force to the sleeves 16 tending to move them up on the rods 15. This causes a like movement of the apron roll 6, and this tightens 35 the mixing apron and draws it against the mixing roll 1. There is also a pressure roll 30 which is located close to the apron roll 5. This is mounted in bearings carried by two sleeves 31 which are slidably mounted 40 upon the rods 8. A spring 32 around each rod 8 is compressed between the associated sleeve 31 and a collar 33 fixed to the rod 8. These springs, therefore, act always on the two sleeves 31 to so move them as to yieldingly push the pressure roll 30 toward the roll 5, and to likewise push the rods 8 in the contrary direction, thereby moving 45 apron roll 4 in the apron tightening direction. The mixing apron 3 after passing 50 under roll 5 passes up between it and roll 30, and thence over roll 30 to roll 4. The roll 30 is so placed with respect to roll 5 that the feed apron passing between those two rolls will be clamped between them 55 from side to side; and thereby the apron is compelled to move at equal rates from side to side at the points where it passes between these two rolls.

The two rods 8 at the ends thereof which 60 are adjacent to the roll 4 are each provided

with a head 9. A rock shaft 40 is mounted in brackets 41 fixed to the adjacent end of the pan, and it has two upwardly projecting arms 42, each containing a slot 43. Into each of these slots a pin 9^a projects which is fixed to the adjacent head 9. This mechanism is for the purpose of equalizing and synchronizing the endwise movements of the rods 8, or, in other words, of compelling them to move equally in the same direction whenever either is moved in the manner to be described.

Two standards 45 are secured preferably to the top of the side members 46 of the mixing mill frame; and in the upper ends 70 of these a rock shaft 47 is mounted. This is provided with two arms 48, and these arms are connected by links 49 with the upper ends of the two rods 15; and a weighted arm 50 is fixed to this shaft in such position that it tends to rock it in the direction which will swing the two arms 15 away from the mixing rolls.

When in the operation of the mixing mill and the described feeding mechanism, a lump of the material being mixed falls onto the apron near one edge, say the front edge thereof, it will be carried up between the apron and the mixing roll. This will cause the front edge of that part of the apron 90 which is in contact with said lump to move a little faster than the corresponding part of the rear edge of the apron. The result will be a little looseness in that part of the front edge of the apron which is between 100 the mixing roll and the apron roll 5, and a little tightening of the front edge of the apron between the mixing roll and the apron roll 4. This may cause the front end of the roll 4 to be drawn toward the roll 5; if it is, 105 the rear end of roll 4 must move equally in the same direction because of the equalizing mechanism described, which connects the two ends of the rods 8. These rods will therefore be moved equally to the left as 110 shown in Fig. 1. This will increase the tension on the two springs 32, and this will result in increasing the clamping action which the pressure roll 30 applies to that part of the apron which is passing between it and 115 the roll 5. Because of this clamping action, the apron as it passes between these rolls must move at equal rates at both edges.

The presence of the lump as described between the mixing roll and the front edge of 120 the apron will also cause the front rod 15 to swing a little away from the mixing roll; but because of the equalizing mechanism connected with the upper ends of both rods 15, these two rods must swing simultaneously and equally. This preserves substantially the parallelism of the roll 6 with the roll 5, and this in an appreciable degree, contributes to the prevention of any lateral movement of the feed apron.

In fact, all of the described parts have such coöperative action that any lateral movement of the feed apron is substantially impossible, however variable may be the 5 size of the lumps of material which fall upon the apron, and however irregularly those lumps may be disposed upon the apron from side to side.

Having described my invention, I claim:

- 10 1. In combination with the mixing rolls of a mixing mill, three apron rolls, viz., two rolls which are located in planes below the mixing rolls, and one roll which is located in a higher plane adjacent to one side of the 15 apron driving mixing roll, fixed bearings for that one of the low apron rolls which is adjacent to the elevated mixing roll, movable bearings for the other two apron rolls, a pressure roll mounted in movable bearings 20 adjacent to the fixed apron roll, an endless feed apron which goes around and contacts with the three apron rolls and passes between the fixed apron roll and said pressure roll, and means for yieldingly acting to 25 move both of the movable apron rolls in the apron tightening direction, and to move the pressure roll toward the fixed apron roll for the purpose of clamping the apron between them.
- 30 2. In combination with the mixing rolls of a mixing mill, an endless feed apron therefor, three apron rolls over which said apron runs, viz., two rolls which are located in planes below the mixing roll and one roll 35 which is mounted in a higher plane and adjacent to the side of the apron driving mixing roll, two pivoted arms which extend upward at an angle toward the apron-driving mixing roll, bearing brackets for the elevated apron roll which are slidably mounted upon said pivoted arms, means for applying yielding pressure to said bearing brackets to move them upward on said arms, and means which, when either of said swinging 45 arms is caused to turn about its pivotal axis, will compel the other of said swinging arms to swing about its pivotal axis at the same time in the same direction and at an equal distance.
- 50 3. In combination with the mixing rolls of a mixing mill, three apron rolls over which said apron runs, viz., two rolls which are located in planes below the mixing roll and one roll which is mounted in a higher plane 55 and adjacent to the side of the apron driving mixing roll, two pivoted arms which extend upward at an angle toward the apron driving mixing roll, bearing brackets for the elevated apron roll which are 60 slidably mounted upon said pivoted arm, means for applying yielding pressure to said bearing brackets to move them upward on said arms, a rock shaft, two arms fixed thereto, and two links which respectively connect said arms and 65 connect said arms and said swinging arms.
4. In combination with the mixing rolls of a mixing mill, an endless feed apron therefor, three apron rolls over which said apron runs, viz., two rolls which are located in planes below the mixing roll and one roll 70 which is mounted in a higher plane and adjacent to the side of the apron driving mixing roll, two pivoted arms which extend upward at an angle toward the apron driving mixing roll, bearing brackets for the elevated 75 apron roll which are slidably mounted upon said pivoted arm, means for applying yielding pressure to said bearing brackets to move them upward on said arms, a rock shaft, two arms fixed thereto, and two links 80 which respectively connect said arms and said swinging arms, and a weighted arm fixed to said rock shaft and acting to turn the same in the direction which will cause the swinging arms to swing away from the 85 mixing rolls.
5. In combination with the mixing rolls of a mixing mill, three apron rolls, viz., two rolls which are located in planes below the mixing roll, and one roll which is 90 mounted in a higher plane and adjacent to the side of the apron-driving mixing rolls, a pressure roll located adjacent and close to that one of the low mixing rolls which is substantially below the elevated apron roll, 95 movable bearings in which said pressure roll is mounted, springs acting on said bearings to move them toward the adjacent apron roll, and an endless feed apron which passes over the three apron rolls and between the pressure roll and the adjacent apron roll and is adapted to be clamped between these two rolls as the pressure roll is moved by said springs.
6. In combination with the mixing rolls 100 of a mixing mill, an endless feed apron therefor, three apron rolls over which said apron runs, viz., two rolls which are located in planes below the mixing roll and one roll which is mounted in a higher plane and adjacent to the side of the apron-driving mixing roll, fixed bearing brackets for that one of the low apron rolls which is adjacent to the elevated apron roll, movable bearing brackets for the other low apron roll, a 110 pressure roll adjacent to the fixed low apron roll, movable bearing brackets for said pressure roll, and springs which act in opposite directions to move the bearing brackets of the pressure roll toward the adjacent 120 apron roll and to resist the movement in the same direction of the movable bearing brackets of the other low apron roll, and an endless feed apron which embraces the three apron rolls and goes between the fixed low 125 apron roll and the adjacent pressure roll.
7. In combination with the mixing rolls of a mixing mill, three apron rolls, viz., one roll which is located adjacent to one side of the apron-driving mixing roll, and two

apron rolls which are located in planes below the mixing rolls, fixed bearings for that one of the low apron rolls which is adjacent to the elevated apron roll, two upwardly 5 inclined swinging arms, bearings for the elevated apron roll slidably mounted upon said swinging arms, means yieldingly pressing said bearings upward on said arms, two parallel endwise movable rods located below 10 the mixing rolls, bearing brackets for one of the low mixing rolls fixed to said rods, a pressure roll located adjacent to the fixed apron roll, bearing brackets for said pressure roll slidably mounted on said endwise 15 movable rods, collars on said endwise movable rods, and springs surrounding said rods and compressed between said collars and the movable bearing brackets of said pressure roll, and an endless feed apron 20 which goes around the three apron rolls and between the fixed apron roll and said pressure roll.

8. In combination with the mixing rolls of a mixing mill, three apron rolls, viz., two 25 rolls which are located in planes below the mixing roll and one roll which is located in a higher plane adjacent to one side of the apron-driving mixing roll, fixed bearings for that one of the low apron rolls which is

adjacent to the elevated apron roll, two pivoted arms which extend upward at an angle 30 toward the apron-driving mixing roll, bearings for the elevated apron roll which are slidably mounted upon said pivoted arms, means for applying yielding pressure to 35 said bearing brackets to move them upward on said arms, movable bearings for the other low apron roll, springs acting to move the last mentioned apron roll in the apron tightening direction, a pressure roll mounted adjacent to the fixed apron roll, movable 40 bearings in which said pressure roll is mounted, an endless feed apron which embraces the three apron rolls and passes between the fixed apron roll and the pressure roll, and means by which the movement of the movable low apron roll toward the fixed low apron roll will increase the pressure of the pressure roll upon the apron 45 which passes between it and the fixed apron roll.

In testimony whereof, I hereunto affix my signature in the presence of two witnesses.

PARK E. WELTON.
